OIL BURNER

Ude P. Udesen, St. Paul, Minn.

Application April 6, 1933, Serial No. 664,705

4 Claims. (Cl. 158—73)

This invention relates to liquid fuel burning apparatus and while particularly adapted in oil burner construction for use with a furnace, it is also applicable to other heating apparatus where liquid fuel is utilized.

It is an object of my present invention to provide simplified and highly efficient liquid fuel burning apparatus which may be manufactured at relatively low cost, which does not require oil pumps and air blowers and which, nevertheless, produces a more efficient atomization of the liquid fuel and a more efficient mixture of the atomized fuel and the combustion-supporting gas.

A further object is to provide an oil burner which will produce a more efficient and consequently more economical combustion of fuel and which, through its inherent structure, may successfully utilize the cheaper hydro-carbon fuels. In many burners now extensively used, liquid fuel is discharged through a minute orifice in the nozzle under pressure produced by an oil pump. A relatively large quantity of air is discharged in an annular stream surrounding said orifice. Mixture of the air and fuel does not take place at the end of the nozzle and consequently ignition and combustion begins several inches away from the burner with the result that combustion of the fuel is far from complete in the fire pot or combustion chamber of the furnace. Furthermore, due to the substantial pressure placed upon the liquid fuel, a very fine orifice must be utilized and consequently the nozzle will be obstructed by the use of the heavier and cheaper fuels, and, in most "gun type" burners, it is impossible to successfully utilize the cheap undistilled fuels.

With my construction, no pressure is placed upon the fuel but the fuel is induced by suction created by a jet of air under pressure which is directed at an angle to the fuel nozzle on the principle of an atomizer. A relatively large orifice for the fuel nozzle can consequently be utilized and there is a very thorough mixture of fuel and air at the discharge end of the fuel nozzle as well as a complete atomization of the liquid fuel.

Another and more specific object is the provision of oil burning apparatus wherein the flow of fuel is induced and atomized by the discharge of a small jet of air under pressure and wherein a uniform flow of said fuel is obtained through the cooperation of said induction and a feed controlling mechanism operating on the "vacuum tank" principle.

These and other objects and advantages of the

invention will more fully appear from the following description made in connection with the accompanying drawings, wherein like reference characters refer to the same parts throughout the various views, and in which:—

Fig. 1 is an assembly view showing a form of my apparatus applied to a conventional type of furnace;

Fig. 2 is a view partly in vertical section showing the burner proper applied in an opening in one of the furnace walls;

Fig. 3 is a cross section taken approximately on the line 3—3 of Fig. 2 and showing the cross head which provides passages for air, liquid fuel and gas for supplying the starter or pilot light;

Fig. 4 is a horizontal section taken through the cross head and showing the hand operated valve for regulating the flow of liquid fuel;

Fig. 5 is a detail section showing a suitable starter or pilot light construction, associated with the outer portion of the fuel induction adjacent the nozzle;

Fig. 6 is a vertical section showing the construction of the feed controlling mechanism which acts on the "vacuum tank" principle;

Fig. 7 is a cross section taken approximately on the line 7—7 of Fig. 6; and

Fig. 8 is a detail view showing the pressure actuated valve at the lower end of the tank.

As shown in the drawings the oil burner proper of my apparatus is mounted in a suitable aperture provided in the door D of a conventional furnace F. It will, of course, be understood that the burner may be mounted in a suitable manner in any of the other walls of a furnace or upon any suitable support disposed within the lower portion of a furnace.

My burner proper includes, as shown, a tubular truncated conical casing or nose 15 which extends inwardly of the furnace and is provided with an out-turned attachment flange 15a which may be secured to the furnace wall or door. Casing 15, as will later be explained, forms a relatively large air duct which tapers from its outer to its inner end. A nozzle carrying member 16 which, as shown, is in the form of a casting, is attached to the outer end of casing 15, said member as shown comprising a hollow open-ended truncated conical shell which carries internally at its inner end a cross head 17 which may be integrally cast with the shell. A very small fuel conduit 18 is connected with and supported by the center of cross head 17, extending longitudinally through the nose or casing 15 and terminating in a somewhat downwardly inclined nozzle 55.

18a which is disposed exteriorly of the nose 15, and substantially at the axial center thereof. One of the horizontal arms of the cross head 17 is tapped to form a fuel passage 17a communicating with the attached end of conduit 18 and this passage is connected by suitable fittings with an oil line 19. Directly below the fuel conduit 18 and secured to the lower vertical arm of cross head 17 is a small air conduit 20 extending longitudinally through nose or casing 15 and terminating in a somewhat upwardly directed nozzle 20a disposed just below and slightly rearwardly of fuel nozzle 18a and in juxtaposition therewith to produce an atomizing effect in cooperation with the fuel nozzle. The last mentioned arm of cross head 17 is tapped to form a short air passage 17b in communication with the attached end of air conduit 20. This passage is connected by suitable fittings with an air supply pipe 21. Suitable starting or igniting mechanism is provided adjacent the nozzles 18a and 20a and as shown I provide a small gas burner comprising a conduit 22 secured to and supported from the upper vertical arm of the cross head 17 and extending longitudinally within nose or casing 15 and having attached to its outer end a tubular burner member 23 terminating in a downwardly directed nozzle 23a which is disposed in juxtaposition to the fuel nozzle 18a. The end of conduit 22 is longitudinally ribbed or recessed at 22a to afford a Bunsen burner effect in supplying air by induction and has a restricted port 22b through which gas is discharged within the tubular burner member 23. Burner member 23 may be provided with one or more air intake ports 23b to permit entrance of additional combustion supporting gaseous medium such as air therewithin. The upper vertical arm of cross head 17 is tapped to form a gas passage 17c in communication with the secured end of conduit 22 and a gas line 24 is connected by suitable fittings with said passage 17c.

The truncated conical shell 16 constituting the outer portion of the burner casing is provided at its outer end with a series of relatively deep, air entrance recesses 16a, said recesses extending from the end inwardly and longitudinally. A cap 25 closes the outer end of shell 16 and carries a series of circumferentially spaced inwardly extending shutters 25a of approximately the width of air entrance recesses 16a, which as clearly shown in Fig. 2, are adapted to adjustably cooperate with the recessed portions of the shell to vary the air entrance area. The circumferentially spaced shutters of cap member 25 engage the peripheral wall of shell 16 and enable the cap to be oscillated relatively to the shell. The center of the cross head 17 at the rear thereof is tapped to form a valve chamber 17d extending axially of nose 15 and shell 16 and provided with a suitable valve seat (see Fig. 4). A needle valve 26 is mounted in said chamber, said valve having its stem screw threaded in a sleeve 27 and said stem is projected axially of shell 16 through a central aperture formed in the cap 25. A knurled knob 26a is attached to the outer end of the valve stem and a coiled compression spring 28 is interposed between said knob and cap 25 to yieldingly hold the cap inwardly against the shell 16.

The flow of fuel through conduit 18 and nozzle 18a is induced by the discharge of compressed air from the air nozzle 20a, no pump or other fuel circulating means being provided. To assure a uniform flow of fuel regardless of the quantity of fuel in the supply tank and to prevent discharge of fuel when the burner is not in oper-

ation or when the discharge of compressed air is arrested, I provide an efficient feed controlling mechanism as shown in Figs. 6 to 8. Said mechanism comprises a small cylindrical tank 30 which may be mounted on a suitable support 31 and which is closed at its upper end by a cap 32, shown in the form of a casting. Cap 32 includes a horizontal enlargement 32a affording a radial passage communicating with an axially disposed valve chamber 32b which is in communication 10 with the interior of tank 30 through a nipple 33. Nipple 33 has an axial port 33a at its upper end which communicates with a series of radial discharge ports 33b (see Figs. 6 and 7). The passage within enlargement 32a is connected with 15 the liquid fuel supply tank T by a pipe line 34. A ball valve 35 is mounted within valve chamber 32b and is adapted to fit a concave valve seat at the upper end of nipple 33. A small cylindrical housing 36 is secured to the top of cap 32 and contains an electro-magnetic coil 37 disposed axially of nipple 33 and having a depending metal core 37a which extends through and tightly fits a small plug 38 constructed of copper or some other non-magnetic material. The lower end of core 37a is disposed slightly above the ball when the latter is in closed position and when coil 37 is electrically energized, ball 35 will be lifted from its seat by the magnetic flux created in core 37a. 30

A float 39 is mounted within tank 30 and rigidly carries an up-standing stem 40 terminating in a needle valve 40a which is disposed axially of nipple 33 and seats against an annular shoulder in the port 33a, said seat being disposed above the radial discharge ports 33b. A breather tube 41 is secured to cap 32 to provide a passage between the interior of the tank 30 and the atmosphere surrounding the tank 30. A valve equipped discharge passage 30a is formed preferably axially of the bottom of tank 30 and communicates with a shallow chamber 42 which underlies the tank. The bottom of chamber 42 is defined by a diaphragm 43 sealed at its edges against a suitable annular shoulder provided in a casting or other member 44. Member 44 is 45 constructed to form an enlarged passage or chamber 44a through which compressed air passes for supplying air nozzle 20a of the burner.

A ball valve 45 is adapted to engage an annular seat formed in discharge passage 30a and as shown said valve is connected with the end of a leaf spring 45a which normally urges the valve against its seat. Diaphragm 43 is provided with an upstanding stud 43a which extends through the lower portion of passage 30a and is adapted to engage and lift ball valve 45 when pressure from the under side of the diaphragm is above a predetermined degree.

The shallow chamber 42 disposed below tank 30 communicates with a vertically disposed segmental-shaped chamber 46 disposed at one side of the tank and extending substantially the full height of the tank. The tank and chamber 46 may be conveniently formed by an integral casting. A fuel outlet passage 46a communicates with the upper portion of chamber 46 at a point some distance above the maximum liquid level of tank 30. Passage 46a is connected with the oil line 19 which supplies fuel nozzle 18a of the burner.

The magnetic coil 37 is connected through a heat regulating mechanism, such as the room thermostat R, to a source of electrical energy, such as the battery B, by means of wires 37b and 37c, 75 as shown.

For use as a source of compressed air, an air compressor is provided such as the compressor unit illustrated in Fig. 1 and including the frame 50, cylinder 51, air tank 54, connecting rod 60, crankshaft 63, pulleys 66 and 68, and motor M, all of these parts being associated with each other in accordance with common practice.

An air conduit 74 connects the compressed air reservoir with the diaphragm chamber 44a of the casting 44.

The electric motor M is connected through wires 80 to the wires 37b so as to be energized and de-energized coincidentally with the magnetic coil 37 in response to operation of the thermostat R, whereby the valve 35 for controlling the flow of fuel into the tank 30 will be opened and closed as the motor M is respectively started and stopped.

Operation

With the apparatus operatively assembled as shown in Fig. 1, the motor M will be started and the ball valve 35 lifted by the electro-magnet when heat is needed. Air is then compressed by the compressor unit and is discharged through the small air nozzle 20a of the burner, inducing a flow of the liquid fuel from the chamber 46 of the fuel controlling mechanism through the small fuel nozzle 18a, thoroughly atomizing the induced fuel and mixing air therewith. The flame from the starting burner 23 ignites the combustible mixture and a very hot flame is produced in my burner construction and is projected substantially axially from the nose or casing 15. The amount of fuel induced may be regulated by the needle valve 26.

It will be noted that where a starting burner of the type illustrated is utilized the heat from the heat-conductive burner member 23 will be transmitted to the outer portion of the fuel conduit 18, serving to vaporize to some extent the fuel before it is atomized and ignited.

The natural draft of the furnace assisted materially by the inductive effect from the discharge of nozzle 20a produces a strong flow of combustion supporting air through the shell 16 and nose 15. This incoming air surrounds the fuel atomizer and materially aids the combustion, mixing with the finely atomized liquid particles of fuel. This air supply may be regulated by oscillating cap 25 on shell 16 to vary the size of the air intake recesses 16a.

With reference to the operation of the feed controlling mechanism shown in Figs. 6 to 8, it will be seen that no fuel can enter tank 30 until ball 35 has been lifted by the magnetic coil. It will further be seen that the float 39 maintains a substantially constant level of fuel in the tank 30. The diaphragm actuated valve 45 prevents passage of fuel from tank 30 into discharge chamber 46 until the pressure of the air discharged through nozzle 20a is adequate to properly atomize the fuel. Thus a substantially uniform flow of fuel drawn from the chamber 46 is provided by the induction method. Induction of fuel will be arrested promptly upon decrease of the air pressure below the requisite degree and will therefore be cut off very promptly when the circuit through the motor is broken. It will be noted that the fuel nozzle 18a is positioned considerably above the fuel level of the tank 30 and slightly above the level of the discharge passage 46a leading out of discharge chamber 46.

From the foregoing description, it will be seen that I have provided a very efficient and eco-

nomic oil burner construction which may be readily installed in most furnaces commercially sold at this time and which will produce a very efficient and thorough fuel combustion.

It will be noted that in the atomization of the liquid fuel a small strong jet of air is directed at an acute intersecting angle against the tip of the fuel nozzle 18a, thereby producing a suction upon the fuel conduit and thoroughly atomizing the induced fuel immediately adjacent the tip of the fuel nozzle. There can be no accumulation or dripping of fuel from nozzle 18a since the air jet strikes the nozzle tip and drives off the liquid before it can accumulate. It will also be apparent that a very thorough mixture of the atomized fuel and air takes place immediately adjacent the tip of nozzle 18a, whereby combustion extends from the nozzle tip outwardly axially of the burner casing in the form of an elongated small flame. Substantially complete combustion is effected adjacent the nozzle, while with "gun type" oil burners a substantial amount of the fuel is not atomized or mixed with air until the discharged fuel and air have struck a baffle or wall of the fire box removed some distance from the nozzle.

Attention is called to the efficiency of the burner adjustments and the ease with which the same may be made. The shutter cap 25 mounted on the exterior shell of the burner casing regulates the amount of air supplied to the burning fuel as a result of natural draft. The strong draft of air past the nozzle 20 induced primarily by the discharge of air under pressure from nozzle 20 but substantially increased by the flow of air caused by the flue action of the furnace has, of course, an effect upon the induction of fuel through nozzle 18a. In other words, assuming the needle valve 26 for directly controlling the fuel supply to be set, when additional air is admitted by further opening shutter cap 25, a proportionately greater amount of fuel will be induced due to the increase in draft brought about by flow of air created by natural draft. Extensive combustion tests have been made and it has been found that when the burner is properly set for efficient combustion with the cap substantially closed, the combustion will have substantially the same efficiency when the cap is moved to substantially full open position.

The proportionate discharge of fuel may, of course, be easily varied by adjusting the needle valve 26 through the manipulation of the handle 26a conveniently disposed through the outer end of the air regulating cap 25. A co-operation of the induced and atomized fuel supply with the air regulating means in the burner shell thus provides a very efficient burner adjustment.

It further will be seen that with the induced or suction-operated flow of fuel in my burner, the fuel nozzle 18a will be provided with a relatively large orifice in contrast to the orifice of a pressure-operated fuel nozzle. Consequently my fuel nozzle will not be obstructed by cheap and heavier grades of hydrocarbon fuel and I have successfully utilized undistilled hydro-carbons with my device.

It will be understood that various changes in the form, details and arrangement of parts may be made, all without departing from the scope of my invention.

What is claimed is:—

1. In a liquid fuel burner, a small bore fuel nozzle, a second small bore nozzle connected with a source of air under pressure and disposed in

juxtaposition to said fuel nozzle to produce a cross jet and suction effect thereupon, a gravity actuated fuel supply and a fuel feed controlling unit, comprising a feed chamber, temperature responsive means for controlling the discharge of fuel from said supply to said chamber, said chamber having a discharge outlet adjacent its upper end, a conduit connecting said outlet and said fuel nozzle, and float controlled means in said chamber for maintaining the level of liquid fuel considerably below the level of the highest point in said conduit and below the fuel nozzle whereby flow of fuel through said nozzle will be shut off when the induction effect from the other nozzle falls below a certain point.

2. The structure set forth in claim 1, wherein the fuel feed controlling unit comprises a single chamber or reservoir, and wherein said temperature responsive means includes automatically actuated valve means at the upper end of said chamber and said float controlled means is slidably mounted within said reservoir.

3. In an oil burner for use with a furnace having natural draft, a relatively large air conduit mounted in a wall of said furnace whereby said draft will induce a flow of air therethrough, said conduit extending into said furnace and tapering toward its forward or delivery end, a small bore fuel nozzle connected with a source of fuel and disposed longitudinally of said air conduit and directed forwardly and downwardly

at its discharge end and terminating forwardly of said conduit, a small bore air nozzle also extending longitudinally of said conduit and terminating slightly rearwardly of the discharge end of said fuel nozzle to produce a cross jet and suction effect thereupon, said last mentioned nozzle being connected with a source of air under pressure, the recited relationship of said nozzles being such that dripping of liquid fuel upon said air nozzle is prevented.

4. In an oil burner for use with a furnace having natural draft, a relatively large air conduit mounted in a wall of said furnace whereby said draft will induce a flow of air therethrough, said conduit converging toward its inner and delivery end, a very small bore air nozzle disposed longitudinally of said air conduit and terminating at a point beyond the inner end thereof and connected with a source of air supply under pressure, and a very small bore fuel nozzle connected with a source of fuel and also extending substantially longitudinally of said air conduit and disposed in juxtaposition to said air nozzle beyond the inner end of said conduit whereby fuel will be induced and atomized, said air conduit being so disposed with reference to said nozzles that induction of air through said conduit will be assisted by said atomizing action and the incoming air will surround and support the flame produced.
